CLAIM

The ornamental design for a wheeled walker for pets, as shown and described.

DESCRIPTION

FIG. 1 is a front, side and top perspective view of a wheeled walker for pets, showing our new design.

FIG. 2 is a rear, side and bottom perspective view thereof.

FIG. 3 is a left side view thereof.

FIG. 4 is a right side view thereof.

FIG. 5 is a top plan view thereof.

FIG. 6 is a bottom plan view thereof.

FIG. 7 is a front elevational view thereof.

FIG. 8 is a rear elevational view thereof.

FIG. 9 is a top plan view thereof, wherein the back belt section is in an alternate position as compared to FIG. 5; and,

FIG. 10 is a reference diagram thereof, showing use.
The broken lines shown in the figures depict portions of the wheeled walker for pets that form no part of the claimed design.
